(57) **CLAIM**

The ornamental design for a mascot anthropomorphic robot as shown and described.

DESCRIPTION

The patent or application file contains at least one drawing executed in color. Copies of this patent or patent application publication with color drawing(s) will be provided by the Office upon request and payment of the necessary fee.

FIG. 1 is a front perspective view of the first embodiment of a mascot anthropomorphic robot, showing my new design; FIG. 2 is a left side elevational view of the mascot anthropomorphic robot;

FIG. 3 is a rear elevational view of the mascot anthropomorphic robot;

FIG. 4 is a right side elevational view of the mascot anthropomorphic robot;

FIG. 5 is a top plan view of the mascot anthropomorphic robot;

FIG. 6 is a bottom plan view of the mascot anthropomorphic robot; and,

FIG. 7 is a front perspective view of the second embodiment of a mascot anthropomorphic robot, wherein articulated portions of the mascot anthropomorphic robot are shown in alternate positions.
